FIGURE 1 is a perspective view of an auxiliary vehicle lamp housing showing my design, taken from a forward vantage point;

FIGURE 2 is a side perspective view of the device of FIGURE 1 taken from a slightly raised vantage point, the side opposite that shown being the same in appearance; and

FIGURE 3 is a perspective view of the device of FIGURE 1 taken from a rearward vantage point.

The lens of the vehicle lamp is shown in broken line in FIGURES 1, 2 and 3 for illustrative purposes only.

I claim:

The ornamental design for an auxiliary vehicle lamp housing, as shown and described.
